US0D1084179S

(12) **United States Design Patent** (10) **Patent No.:** **US D1,084,179 S**
(45) **Date of Patent:** **** Jul. 15, 2025**

(54) **RETRACTABLE SWING TRAINER**

(71) Applicant: **Yaosong Zhang**, Hangzhou (CN)

(72) Inventor: **Yaosong Zhang**, Hangzhou (CN)

(**) Term: **15 Years**

(21) Appl. No.: **29/966,053**

(22) Filed: **Sep. 30, 2024**

(51) **LOC (15) Cl.** **21-02**

(52) **U.S. Cl.**

USPC **D21/715**

(57) **CLAIM**

The ornamental design for a retractable swing trainer as shown and described.

DESCRIPTION

FIG. 1 is a front, left, and top perspective view of a retractable swing trainer, showing my new design;

FIG. 2 is a rear, right, and bottom perspective view thereof;

FIG. 3 is a front view thereof;

FIG. 4 is a rear view thereof;

FIG. 5 is a left side elevation view thereof;

FIG. 6 is a right side elevation view thereof;

FIG. 7 is an enlarged top plan view thereof;

FIG. 8 is an enlarged bottom plan view thereof; and,

FIG. 9 is a front, left, and top perspective view showing the retractable swing trainer a position of use.

The broken lines depict portions of the retractable swing trainer that form no part of the claimed design.

1 Claim, 9 Drawing Sheets
